No. 12,269

May 17, 1881

Fig. 1.

Fig. 2.

UNITED STATES PATENT OFFICE.

G. WALTER TURNER, OF BOSTON, AND OLIVER H. ARNO, OF WILMINGTON,
MASSACHUSETTS.

DESIGN FOR A MECHANICAL MUSICAL INSTRUMENT.

SPECIFICATION forming part of Design No. 12,269, dated May 17, 1881.

Application filed July 16, 1880. Term of patent 3½ years.

To all whom it may concern:

Be it known that we, G. WALTER TURNER and OLIVER H. ARNO, respectively of Boston and Wilmington, in the counties of Suffolk and Middlesex and State of Massachusetts, have invented and produced a certain new and original Design for Mechanical Musical Instruments, of which the following is a full, clear, and exact description, reference being had to the accompanying photographs, forming part thereof.

Figure 1 is an end view of our newly-designed case; Fig. 2, a front elevation of the same.

This design of a mechanical musical instrument-case consists of a cubical-shaped lower portion, A, surrounded at its base by a molding-strip, B, and projecting base-board C, and surmounted at its top by a casing, D, which is a continuation of the casing A, and has its front provided with a plate, F, of glass, arranged either in a straight or a curved line in relation to the front of the case. This glass plate F, as shown, presents a convex exterior

surface, and at its lower edge the case is continued with an ogee-curved portion, G, to the upper part of the cubical portion A.

H is an oblong opening in the top of the case.

Having now described our design for cases for mechanical musical instruments, what we claim, and desire to secure by Letters Patent, is—

The design for a case for mechanical musical instruments, herein shown and described, the same consisting of a cubical lower portion, A, surrounded by a base-board and molding-strip, and an upper portion, D, having a front, F, and ogee-curved portion G, all substantially as described.

In testimony whereof we have hereunto set our hands in the presence of two subscribing witnesses.

G. WALTER TURNER.
OLIVER H. ARNO.

Witnesses:

WILLIAM S. BELLOWES,
EDWIN W. BROWN.
